(57) **CLAIM**

I claim the ornamental design for a surveillance camera lens, as shown and described.

DESCRIPTION

FIG. 1 is a top, front and left side perspective view of a surveillance camera lens of the present invention;

FIG. 2 is a front view thereof;

FIG. 3 is a right side view thereof;

FIG. 4 is a left side view thereof;

FIG. 5 is a top view thereof; and,

FIG. 6 is a bottom view thereof.

The rear view has been omitted and forms no part of the claimed design.

The ornamental design which is claimed is shown in solid lines in the drawings. Any broken lines in the drawings are for illustrative purposes only and form no part of the claimed design.
